Des. 2363

Wm. H. Roberts of Hartford, Conn.
Letters Patent, No. 2363, Dated July 17, 1866.
Design for Burial basket.

The schedule referred to in these Letters Patent and making part of the same:

Of which the following may concern:

I, Wm. H. Roberts of the City and County of Hartford and State of Connecticut, have invented, or discovered, a new and original Design for Burial basket; and do hereby declare that the following is a full and exact description of the same, referring to the accompanying photographic illustrations on which the same letters indicate like parts.

On the accompanying illustrations is shown a new and original Design for a Burial basket;

The following panelled side, embellished with ornamental molding,

is of plain, round, curved, convex

and concave sides, and embellished with ornamental molding.

At C of plain round concave curved side.

Are plain raised, round concave curved panels, surrounded or embellished with plain edges, the whole confined to produce a new and original Design for a Burial basket.

That I claim and desire to secure by Letters Patent, is, the Design for a burial basket substantially as set forth and described:
